UNITED STATES PATENT OFFICE

119,819

DESIGN FOR A SHOE HEEL

Herman E. Morse, Akron, Ohio, and Clarence L. White, Windsor, Vt., assignors to Wingfoot Corporation, Wilmington, Del., a corporation of Delaware

Application February 3, 1940, Serial No. 89,990

Term of patent 7 years

To all whom it may concern:

Be it known that we, Herman E. Morse and Clarence L. White, citizens of the United States, residing, respectively, at 572 Vinita Avenue, Akron, in the county of Summit, and State of Ohio, and 17 Union St., Windsor, in the county of Windsor and State of Vermont, have invented a new, original, and ornamental Design for a Shoe Heel, of which the following is a specification, reference being had to the accompanying drawing, forming part thereof.

Fig. 1 is a bottom plan view of a shoe heel showing our new design, and

Fig. 2 is a section on the line 2—2 of Fig. 1.

We claim:

The ornamental design for a shoe heel, as shown.

HERMAN E. MORSE,
CLARENCE L. WHITE.
